[57] CLAIM

The ornamental design for a serving tray, as shown and described.

DESCRIPTION

FIG. 1 is a top plan view of a serving tray showing my new design;

FIG. 2 is a right side elevational view thereof, the side opposite being identical thereto;

FIG. 3 is an end elevational view;

FIG. 4 is a bottom plan view of one half thereof, the other half being a mirror image;

FIG. 5 is a sectional view taken along the line 5—5 in FIG. 2; and

FIG. 6 is a sectional view taken along the line 6—6 in FIG. 2.

The drawings are stippled to indicate surface texture.

fig. 4.

fig. 5.
